(73) Assignee: **Moriyama Sangyo Kabushiki Kaisha, Tokyo (JP)**

(57) **CLAIM**

The ornamental design for a light emitting element, as shown and described.

DESCRIPTION

FIG. 1 is a top perspective view of a light emitting element showing our new design;

FIG. 2 is a top plan view thereof;

FIG. 3 is a back view thereof;

FIG. 4 is a front view thereof;

FIG. 5 is a right side view thereof, the left side being a mirror image thereof;

FIG. 6 is a bottom plan view thereof;

FIG. 7 is a bottom perspective view thereof; and,

FIG. 8 is an illustrative perspective view showing a light emitting element surrounded by a translucent or transparent cylindrical cover and in combination with a number of like elements. The cylindrical cover and the additional light emitting element are shown in broken lines and form no part of the claimed design.
